FOUNTAIN STRIPER

Filed Nov. 5, 1934

UNITED STATES PATENT OFFICE

2,041,022

FOUNTAIN STRIPER

Martin Rasmussen, Los Angeles, Calif.

Application November 5, 1934, Serial No. 751,461

5 Claims. (Cl. 91—62.6)

This invention relates to and has for an object the provision of an improved type of fountain stiper for the application to ornamented surfaces of stripes formed of pigment or water color paints arranged in a compact form, simple in form, economical in cost and operation, and capable of adjustment for forming a single stripe of desired width or a plurality of parallel stripes, in a single operation.

10 To this end my invention contemplates the provision of a tubular body closed at its opposite ends and provided with a manually adjustable plunger with an operating stem projecting from one end thereof and a removable closure at its 15 other end whereby a quantity of paint may be inserted in the body and fed outwardly therefrom when pressure is created in the body by movement of said plunger.

A particular feature of the invention consists 20 in the provision of a sensitive adjustment whereby an applicator wheel carried on the removable closure at the end of the body may be adjusted relative to an outlet for the paint, for regulating the flow of the paint from the body.

25 Another object is to provide on said closure an applicator wheel having diagonally disposed or herringbone serrations, or millings, for receiving the paint from the body, from which the paint is transferred to a surface to be striped, as the 30 wheel is rotated over the surface.

A further object is to provide a plunger formed 35 of compressible material such as cork, felt, rubber or the like, confined on the plunger stem between a pair of plates or washers, and adjustable, so that when the plunger head is longitudinally compressed it will be expanded radially and thereby compensate for any wear on its periphery which may be occasioned by constant and continued use. Other objects may appear as the 40 description progresses.

I have shown a preferred form of device, embodying my invention, in the accompanying drawing, subject, however, to modification, addition and abridgment, within the scope of the appended 45 claims, without departing from the spirit of my invention.

In said drawing:

Fig. 1 is a perspective view of the assembled device operatively positioned upon a surface to be 50 striped;

Fig. 2 is a longitudinal section, in elevation, of the same;

Fig. 3 is a transverse section of the same on line 3—3 of Fig. 2;

55 Fig. 4 is a fragmentary longitudinal section, at right angles to the plane of Fig. 2, on line 4—4 of Fig. 2;

Figs. 5, 6 and 7 are views of different forms 60 of applicator wheels capable of use in connection with the stiper shown.

The device includes a tubular body 1 of circular cross section, a rear end closure 2 detachably held on the body, a plunger 3 slidably held in said body, an applicator head 4 detachably held on the front end of the body, a universally adjustable guide 5 and an adjustable guide support 6 carried on the body 1.

Plunger 3 includes a stem 7 having a finger button 8 on its outer end and a head 9 on its inner end formed of cork, felt, rubber or other compressible material. Closure 2 is preferably threaded internally of its flange 10 so as to screw onto the externally threaded end portion of body 1, and said closure is bored centrally so as to slidably receive the extended stem 7.

15 Plunger head 9 is adjustably held on the inner end of stem 7 between a pair of spaced washers 11 and 12, and nuts 13 and 14, respectively, are threaded on said stem adjacent said washers so that the head may be longitudinally compressed 20 and correspondingly expanded radially for causing the periphery of the head to frictionally engage the inner periphery of the body 1.

The front end of the body 1 is also externally threaded to detachably receive a collar 15, as 25 shown in Fig. 2, and the applicator head 4 is externally threaded at its rear end so as to detachably engage a portion of said collar. Applicator head 4 is of tubular cross section corresponding to body 1 externally and internally and has an end 30 wall 16 with a centrally formed inwardly extended boss 17 which is bored and threaded to receive a screw 18 having a head 19.

The applicator wheel 20 is rotatably held at 21 between and on a pair of spaced arms 22 and 35 23 formed on the lower portion of a bracket or holder 24 which is adjustably carried on the front end of head 4. Said bracket is of rectangular cross section and is slidably in a diametrical groove 25 and has an elongated aperture 26 through which the screw 18 extends while the head 19 overlies the outer surface of the bracket, as shown in Figs. 2 and 4. The upper end of bracket 24 has a forwardly projecting lug 27 thereon in which an adjusting screw 28 is 40 threaded and the inner end of said screw abuts or is otherwise associated with the head 19 of screw 18 in such a manner that the turning of screw 28 in one or opposite directions will adjust the wheel 20 outwardly from the head 4, 45 inwardly and outwardly, as may be desired.

By reference to Fig. 2 it will be noted that the forward end of head 4 has a slit 29 therein into which the wheel 20 projects so as to come in contact with the paint which is contained in the 55 body 1 and head 4. The wheel 20 is adjustable inwardly or outwardly of said slit by means of a knurled button or knob 30 on screw 28 to an extent depending upon the thickness or density of the paint used. Obviously a water color paint 60

will require that the wheel 28 be adjusted very close to the margins of the slit 29 in order to prevent leakage, while a thicker paint will require a looser adjustment of the wheel.

5 The guide holder 6 is preferably formed of a split ring with laterally extended abutting ends 31 and 32 connected by means of a bolt 33, and diametrically opposite said ends a post 34 is rigidly secured to and extends radially from the 10 ring, as shown in Fig. 1, for holding the guide 5 at desired angles relative to the body 1 and to a supporting surface as at 35. The guide 5 may be of any suitable form which will render it adaptable to universal use, regardless of the position of a stripe on a surface. As shown, said guide may be bent into such form as to provide end portions 36 and 37 and an intermediate portion 37' whereby the guide may be adjustably held in the post 34 at one of the end portions 15 and the other end portion may be disposed adjacent an edge of the surface to be striped. The post 34 is longitudinally bored and threaded to receive set screw 38 and is diametrically bored at right angles, as at 39 and 40 for selectively receiving the end portion 37 of the guide 5, so as to render the guide universally adjustable relative to an edge or portion of an adjacent plane surface which it may be desired to stripe.

As shown in Figs. 5, 6 and 7, the applicator 30 wheels 20 may be of different form so as to apply narrow, wide or multiple stripes to a surface, and to this end the applicator head 4 is provided in several different forms which are selectively attachable to the body 1. The wheel 28 may have 35 a pair or more of striping surfaces as at 39 and 40 in Fig. 5, of corresponding width, or of different width as shown in Fig. 6 at 41 and 42, or a single surface 43 as shown in Fig. 7, of substantial width, or otherwise. For multiple striping the paint applying surfaces are separated by annular grooves as at 44, and in all cases said surfaces are milled diagonally as shown in Figs. 40 5 and 6 or herringbone-like as in Fig. 7.

In operation, a selected applicator head 4 with 45 a suitable applicator wheel 20 is attached to the forward end of body 1 after said body forwardly of the plunger head 8 has been filled with a suitable paint, and a suitable guide 5 is attached to the holder 34 and adjusted so that an outer 50 end portion thereof will engage a margin, side or portion of the surface to be striped or a surface adjacent thereto. The plunger 8 is then forced inwardly so as to compress the paint in the forward end of the body, and the wheel 28 is adjusted inwardly or outwardly relative to the body 1 so as to freely feed the paint from the 55 interior of the body to the periphery of the wheel. When the device is positioned as shown in Fig. 1, or otherwise according to obtaining conditions, 60 and moved forwardly or backwardly over a surface, as at 35, the paint will be received and carried by the milled periphery of the wheel and applied to the surface of 35 in the form of a stripe 45.

65 Obviously, as the paint is used, the plunger 8 may be intermittently moved forwardly in the body for maintaining sufficient pressure to expel the paint in a striping operation. The device is readily cleaned by removing the end closure 2, the applicator head 4 and the plunger 8, and said plunger may be adjusted to compensate for wear 70 on the periphery of its head 8 by tightening the

nut 13, thereby compressing the head longitudinally and expanding the same radially.

What I claim, is:

1. A fountain striping device comprising: a tubular body, a plunger slidable therein, a head forming a closure for an end thereof and having an outlet, a bracket diametrically slidable on said head in a plane at right angles to the axis of said body, a rotatable applicator carried by said bracket and having its periphery disposed adjacent said outlet, and cooperating means fixed to said head and adjustable on said bracket, for adjusting said applicator relative to said outlet, in a striping operation. 10

2. A fountain striping device comprising: a tubular body, a plunger slidable therein, a head forming a closure for an end thereof and having an outlet, a bracket diametrically slidable on said head in a plane at right angles to the axis of said body, a rotatable applicator carried by 20 said bracket and having its periphery disposed adjacent said outlet, and cooperating means fixed to said head and adjustable on said bracket, for adjusting said applicator relative to said outlet, in a striping operation, and a collar secured 25 to adjacent ends of said body and said head for detachably connecting said members for operation.

3. A fountain striping device comprising: a tubular body, a plunger slidable therein, a head 30 forming a closure for an end thereof and having an outlet, a bracket diametrically slidable on said head, a rotatable applicator carried by said bracket and having its periphery disposed adjacent said outlet, and cooperating means fixed 35 to said head and adjustable on said bracket, for adjusting said applicator relative to said outlet, in a striping operation, and a collar secured to adjacent ends of said body and said head for detachably connecting said members for operation 40 40 to adjacent ends of said body and said head for detachably connecting said members for operation, and a closure detachably secured to the other end of said body, through which a portion of said plunger is extended for manual operation whereby to compress a quantity held in said body for discharge through said outlet. 45

4. A fountain striping device comprising: a tubular body, a plunger slidable therein, one end of said body being closed and provided with an outlet, a bracket diametrically adjustable on the exterior of said closed end, an applicator carried by said bracket and having its periphery adjacent said outlet, and adjustment means for said applicator including a member fixed to the end of said body and a member adjustable on said bracket for engagement with said fixed member, 55 for moving the applicator relative to said outlet.

5. A fountain striping device comprising: a tubular body, a plunger slidable therein, a head forming a closure for an end thereof and having an outlet, a bracket diametrically slidable on said 60 head, a rotatable applicator carried by said bracket and having its periphery disposed adjacent said outlet, and cooperating means fixed to said head and adjustable on said bracket, for adjusting said applicator relative to said outlet in 65 a striping operation, and a closure detachably secured to the other end of said body, through which a portion of said plunger is extended for manual operation whereby to compress a quantity held in said body for discharge through said outlet. 70
